(57) **CLAIM**

The ornamental design for a faucet as shown and described.

DESCRIPTION

FIG. 1 is a front perspective view of a faucet, showing my new design;

FIG. 2 is a front elevation view thereof;

FIG. 3 is a rear elevation view thereof;

FIG. 4 is a side plan view thereof;

FIG. 5 is a side plan view thereof;

FIG. 6 is a top plan view thereof;

FIG. 7 is a bottom plan view thereof; and,

FIG. 8 is a second perspective view of a faucet.

The broken lines are included for the purpose of illustrating portions of the article and form no part of the claimed design. The stippling technique used in FIGS. 1-5 and 7-8 is to show depth of the faucet and forms no part of the claimed design.
